EDWIN G. FEEBACK, OF COLUMBUS, OHIO, ASSIGNOR TO THE M. C. LILLEY & COMPANY, OF COLUMBUS, OHIO, A CORPORATION OF OHIO.

CLOSET-TANK CASING.

No. 824,853.

Specification of Letters Patent.

Patented July 3, 1906.

Application filed September 8, 1905. Serial No. 277,594.

To all whom it may concern:

Be it known that I, EDWIN G. FEEBACK, a citizen of the United States, residing at Columbus, in the county of Franklin and State 5 of Ohio, have invented certain new and useful Improvements in Closet-Tank Casings, of which the following is a specification.

This invention relates to a new and useful improvement in closet-tank casings.

Heretofore it has been the general practice in the manufacture of closet-tank casings to form the front and sides from a single piece of wood. This method necessitates thorough steaming of the wood and bending over 15 forms under enormous pressure, a very difficult procedure not always productive of satisfactory results. There are many objections to this form of casing, prominent among which are the expense involved, the liability 20 of the wood splitting, the time consumed in the drying-out process, and the comparatively short life of the finished casing, which, it will be understood, is due to the general source of dampness prevailing about the 25 closet. The action of moisture on bent-wood casings sooner or later causes the same to warp, split, and lose their shape.

It is therefore the object of the invention to overcome to a certain possible degree 30 these objections by producing a casing having separate front and ends connected by curved sawed corner-pieces and covered by a thin sheet of veneering. A casing constructed in this manner is much stronger, 35 more inexpensively and expeditiously produced, and less impervious to moisture, as the several parts of wood when placed in position will have their grains running in different directions, and a substantially laminated 40 structure provided.

With the above and other objects in view the invention consists of the novel details of construction and operation, a preferable embodiment of which is described in the specification and illustrated in the accompanying 45 drawings, wherein—

Figure 1 is a front elevation of the improved tank-casing. Fig. 2 is a transverse vertical sectional view of the same, taken on 50 the line $x-x$ of Fig. 1. Fig. 3 is a horizontal cross-sectional view taken on the line $y-y$ of Fig. 1, and Fig. 4 is an end elevation.

In the drawings, the numeral 1 designates

the front board of the casing, and 2 the end boards. Corner-posts 3 connect the front 55 and end boards. The corner-posts are curved and are sawed from thick pieces, thus obviating all bending. Any suitable means may be employed for securing the corner-posts and ends and front together. However, it has been found that a good moisture-proof glue will produce satisfactory results. After the corner-posts, end boards, and front board have been assembled a thin sheet of veneering is placed over their outer faces and 60 securely glued thereto, thus binding the parts in a homogeneous mass and producing a casing whose front and end walls are formed of several pieces, the grain of the same running 65 in different directions. The rear vertical edges of the end boards 2 are preferably recessed, as at 5, so as to receive the back board 6. A bottom 7 is provided on the casing and may be extended at the front and 70 ends to lend to the ornamental appearance of 75 the casing. It is to be noted that besides the advantages possessed by this casing heretofore mentioned a great saving in material may be had by making the front and end boards 1 and 2 of a less expensive wood than 80 the sheet of veneering 4. It will be obvious that the same general effect and external appearance will be had as if all the parts were made of hard wood, such as it is customary 85 to use in making the veneering.

Having now fully described my invention, what I claim, and desire to secure by Letters Patent, is—

1. A closet-tank casing having its front and ends formed of separate pieces of wood 90 and connected by corner-posts, and a sheet of veneering covering the outer faces of the said parts.

2. A closet-tank casing having its front and ends formed of separate pieces of wood 95 and connected by curved corner-posts sawed from solid blocks of wood, and a sheet of veneering covering the outer faces of the said parts.

In testimony whereof I affix my signature 100 in presence of two witnesses.

EDWIN G. FEEBACK.
